UNITED STATES PATENT OFFICE.

VICTOR H. HARBERT, OF SPRINGFIELD, ILLINOIS, ASSIGNOR TO E. PAYSON SMITH, OF SPRINGFIELD, ILLINOIS.

BRAKE-PIN RETAINER.

Application filed August 11, 1922. Serial No. 581,138.

To all whom it may concern:

Be it known that I, VICTOR H. HARBERT, residing at Springfield, county of Sangamon, State of Illinois, and being a citizen 5 of the United States, have invented certain new and useful Improvements in Brake-Pin Retainers, of which the following is a full, clear, and exact description, such as will enable others skilled in the art to which it 10 appertains to make and to use the same, reference being had to the accompanying drawing, which illustrates the preferred form of the invention, though it is to be understood that the invention is not limited to the 15 exact details of construction shown and described, as it is obvious that various modifications thereof within the scope of the claims will occur to persons skilled in the art.

20 The air brake mechanisms of locomotives and railway train equipment consist of a series of levers connected by rods so as to transmit the power from the air brake cylinder to the wheels. These brake connecting rods have bifurcated ends or jaws which engage the ends of the brake levers and are connected thereto by a pin penetrating the jaws and the lever. The Interstate Commerce Commission requires that 25 eighty-five per cent (85%) of the cars in a train shall have their brake mechanisms operative before the train may move in interstate traffic.

It is readily seen that if these pins should 30 come out that the brake mechanism will not operate but will allow the rods to fall on the road bed and be damaged beyond repair, and furthermore, if the pin connecting the 35 brake beam support should become lost it 40 would allow one end of the brake beam to fall upon the road bed and the other end to project upwardly and derail the truck. Inoperative brakes result in loss of control of train and constant wrecks, and loss of life 45 and limb, as well as result in damage claims.

Various devices, such as nuts, lock washers and spring cotters have been experimented with but experience shows that laborers do not apply such devices at all or only partially tighten the nuts and do not split or 50 separate the legs of the spring cotters. This results in the nuts or cotters becoming lost due to the jolting of the train over the rough track. When the nuts or the cotters are 55 gone the pins will fall out.

One of the objects of this invention is to provide means for preventing the accidental removal of the brake pin and at the same time provide a device which can be readily removed and replaced when occasion 60 requires. This operation can be performed repeatedly without affecting the efficiency of the device.

Another object of the invention is to take up the clearance between the jaws of the 65 connecting rod and the brake lever thus reducing the wear on the pin.

The pins can be made much shorter resulting in considerable saving due to the fact that there are millions of such pins 70 used annually by the railroads. The device may be used with the present standard brake pin with a drilled hole or may be used with a straight smooth shank headed pin without any hole, groove, slot or the like, thus simplifying 75 brake repairs at outlying points along the railroad.

The device cannot be improperly applied, therefore, is fool proof.

The device is applicable to the American 80 Railroad Association standard brake jaws and levers and can be used on old equipment as well as new equipment.

While the device is described as applicable to pins for brake mechanisms for freight 85 train equipment, I do not wish to limit my invention thereto because the device is applicable to machinery which is subject to constant vibration.

It may also be used in connection with 90 nuts or cotters if so desired.

In the drawings:

Fig. 1 shows a side elevation of the end of a brake lever and connecting rod with 95 the invention applied thereon.

Fig. 2 is a plan view of Fig. 1.

Fig. 3 is a side elevation of the end of a connecting rod and brake lever with the device about to be inserted.

Fig. 4 is a perspective view of the device 100 by itself.

Fig. 5 shows a modification wherein one leg of the retainer is longer than the other leg.

Fig. 6 is a detail plan view of the retainer 105 of the modification shown in Fig. 5.

In the drawings 1 represents a standard brake lever, 2 a standard connecting rod having bifurcated portions or jaws 3 and 4 which are connected by pin 5 penetrating 110

the jaws of the lever. Pin 5 is provided with head 6 to hold it in place.

The device consists of U-shaped members 7 and 8 resiliently connected by portion 9 so that the device may be sprung apart, as shown in Fig. 3, when it is being applied to the pin. The outer leg 8 has a rebent portion forming an acute angled flange 10 which when applying the retainer to a pin 10 slides upon the head 6 of the pin 5 and spreads the retainer until it has passed over the pin head when it snaps into place and engages the head of the pin, as shown in Fig. 1, so that it cannot be removed. The 15 leg 7 is bifurcated, as shown in Fig. 4, so that said bifurcations 11 and 12 straddle the pin 5. It will be noted that the ends of the brake jaws are rounded on a radius from the center of the pin, as shown at 13, 20 therefore, the retaining device can be applied to the pin from almost any direction.

This device can be applied to the car without any subsequent action being necessary either to any parts of the car or the 25 device after it is in position. This is accomplished by the resiliency of the device and the relative position of the two bifurcated portions of the device and the pin.

In order to give more resistance and obtain the proper amount of resiliency I provide a corrugation or stiffening rib formed in that portion which connects the two members of the retainer. This is shown in all the figures, particularly in Fig. 4, and designated as 14. This stiffening member may be made in any desired form.

Figs. 5 and 6 show a modification wherein one leg of the U-shaped retainer is longer than the other leg so as to form 40 a lead or wedge when inserting the retainer between the brake lever and the jaws of the connecting rod, so that that portion of the retainer can be fairly well started before the inclined portion 10 comes in contact 45 with the head 6 of pin 5. This elongated portion is deflected somewhat, as shown at 15, Fig. 5. The deflected portion also gives a spring action and forces lever 1 against the jaw 3 thereby taking up any clearance

between the parts and reducing the friction 50 and consequent wear.

It will be noted in Figs. 4 and 6 that the bifurcated portions of the bifurcated leg are narrower at their extremities than at their bases. This is for the purpose of 55 leading or guiding the retainer into proper position when being applied. This feature is advantageous whether one leg of the U-shaped retainer is longer than the other or not. 60

What I claim is:

1. A brake pin retainer comprising two members resiliently connected, the end of one of said members bent to form an acute angled flange. 65

2. A brake pin retainer having two members resiliently connected, one of said members being longer than the other member, said longer member being bifurcated, said bifurcated portions being narrower at their 70 extremities than at their base, the other member being rebent to form an acute angled flange. 75

3. A brake pin retainer having two members resiliently connected, one of said members being longer than the other member and the end portion thereof deflected, the other member being rebent to form an acute angled flange. 80

4. A brake pin retainer having two members resiliently connected, one of said members being bifurcated, said bifurcated portions being narrower at their extremities than at their base, the other of said members bent to form an acute angled flange. 85

5. A brake pin retainer having two substantially parallel members resiliently connected, one of said members being bifurcated, said bifurcated portions being deflected, the other member being rebent to 90 form an acute angled flange. 90

6. A brake pin retainer comprising two members resiliently connected, the end of one of said members bent to form an acute angled flange, and the other of said members being bifurcated. 95

VICTOR H. HARBERT.
